MARY KAVANAGH, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of Design No. 15,561, dated November 18, 1884.

Application filed September 12, 1884. Term of patent 3½ years.

To all whom it may concern:

Be it known that I, MARY KAVANAGH, of the city, county, and State of New York, have invented and produced a new and original 5 Design for a Pattern of a Lady's Costume, (numbered 9,415;) and I do hereby declare that the engraved prints accompanying this specification convey to any one accustomed to using paper patterns a clear understanding of how 10 a garment made up by the pattern will appear.

The design shows a basque and a round walking-skirt. The skirt displays a double box-plaited panel down the center of the front; 15 a deep puff-drapery on each side exhibiting plaits in its upper and lower edges; and a deep, full, puffed back-drapery exhibiting

draping plaits in its front edges and loopings back of the plaits. The basque displays closely-fitted fronts shaping a point at the lower end 20 of the closing and a slight arch over the sides; a deep, closely-fitted back exhibiting under-folded plaits at the lower ends of its middle three body-seams; coat-sleeves, and a standing collar.

What I claim as my invention, and desire to secure by Letters Patent, is—

The design for a lady's costume, as shown in the engraved prints accompanying this specification.

MARY KAVANAGH.
